UNITED STATES PATENT OFFICE.

ABRAHAM BUCKWALTER, HENRY BUCKWALTER, AND JOSEPH H. BUCKWALTER, OF KIMBERTON, PENNSYLVANIA.

IMPROVEMENT IN BRICK-MACHINES.

Specification forming part of Letters Patent No. 35,585, dated June 17, 1862.

To all whom it may concern:

Be it known that we, ABRAHAM BUCKWALTER, HENRY BUCKWALTER, and JOSEPH H. BUCKWALTER, all of Kimberton, in the county of Chester and State of Pennsylvania, have invented certain new and useful Improvements in Machines for Pressing and Molding Bricks; and we do hereby declare that the following is a full, clear, and exact description of the same, reference being had to the accompanying drawings, making a part of this specification, in which—

Figure 1 is a side sectional view of our invention taken in the line $x x$, Fig. 2. Fig. 2 is a horizontal section of the same, taken in the line $x' x'$, Fig. 1. Fig. 3 is a transverse vertical section of the same, taken in the line $y y$, Fig. 2. Fig. 4 is a section of the same, taken in the line $z z$, Fig. 2.

Similar letters of reference indicate corresponding parts in the several figures.

To enable those skilled in the art to fully understand and construct our invention, we will proceed to describe it.

A represents a framing, which may be constructed in any proper way to support the working parts of the machine, and B is a rectangular box, which is formed of two permanent sides, $a a$, connected by two end pieces, $b b$. The two opposite sides of the box are formed by two molds, C C, which slide therein in grooves c made in the sides $a a$. One of the end pieces b of the box B is provided with stops d to prevent the molds being shoved too far through the grooves when the former are adjusted in said box. To the outer surfaces of the sides $a a$ of the box there are attached transversely strips $e e$, one to each side. These strips e are notched at their centers, as shown at e' in Fig. 4, and they bear against a friction-roller, D, attached to a spring, E, which is secured to the framing A. These notched strips e serve as stops for the box B and retain it so that either mold will be held uppermost, the box B being hung on pivots between parallel arms $f f$, attached to the framing A. This device is for sanding the molds preparatory to the pressing of the clay into them, and the operation is as follows: The box B is turned half a revolution at each movement, the roller D being forced by its spring

E into the notch e' adjoining it, and the operator shoves the mold into the upper side of the box B, and then turns the box another half-revolution and withdraws the mold which was previously at the under side of box B and inserts another in its place. At each movement or half-revolution of the box B the mold at the bottom is sanded, the box B being kept supplied with a requisite quantity of sand. This device for sanding the molds will be fully understood by referring to Fig. 4.

F represents a bed or platform on which a sliding bar, G, is placed longitudinally and fitted in suitable guides, $g g$. This bar G has a short cross-head, h , at its inner end, and at the under side of the bar there is a rack, i , into which a pinion, H, gears when the bar G is at work. The pinion H is placed on a shaft, I, the inner bearing of which is fitted in a vertical sliding bar, J, which passes up through the platform F and has the upper end of a toggle, K, attached to it, to which toggle a lever, L, is connected, by moving which the bar J will be operated and the pinion H thrown in or out of gear with the rack i of bar G, as desired.

To the inner end of the bar G a weight, M, is attached by a cord, j , which passes over a pulley, k , and when the pinion H is thrown out of gear with the rack i of bar G the latter is drawn back by the gravity of said weight, the bar being fed forward by the pinion H, when the latter is thrown in gear with the rack of the bar. The shaft I has a pulley, J' , on its outer end, around which a belt, K' , passes, said belt also passing around a pulley, L' , on a shaft, M' , which is the driving-shaft of the machine, and has a bevel-pinion, l , at its inner end, which gears into a horizontal bevel-wheel, m , at the lower end of a vertical shaft, N, which, when the machine is at work, is connected by a clutch, O, with a vertical shaft, P, having a pinion, Q, on its upper end, which gears into a wheel, R, on the upper end of a shaft, T. This shaft T passes centrally through a cylindrical box or hopper, U, which is placed vertically on the framing A and receives the clay to be tempered and pressed into the molds.

On the lower part of shaft T there are secured wheels $V V$, which are provided with

spiral arms or flanges *n*. Six of these arms or flanges are shown to each wheel, but more or less may be used, and spaces *o* are allowed between them, as shown clearly in Fig. 2. Two wheels, *V V*, are also shown attached to the shaft *T*, but more or less of them may be used. Directly above the lower wheel, *V*, there is permanently secured in the box *U* two cross-bars, *p p*. These bars may be connected together at their point of intersection so as to form a hub, *q*, for the shaft *T* to pass through loosely, and the bars *p* are slightly inclined in their transverse section. On the shaft *T* above the wheels *V* there are secured a number of horizontal blades or arms, *X*. (Shown in Fig. 1.)

On the upper part of the framing *A* there are secured two parallel ways, *r r*, having rollers *s* between them. These ways *r r* are in line with the bar *G* on the bed or platform *F* and in the same horizontal plane with the latter, and said ways extend underneath and beyond the box or hopper to the end of the framing, the rollers *s* being underneath the box or hopper.

To the lower part of the box or hopper *U* there are attached two parallel bars, *t t*, through which a horizontal rod, *u*, passes, and has upon it between the bars *t t* a series of drops, *v*, placed loosely, the front ends of which are heavier than the back ends, so that the former will by their own gravity press upon the molds as the latter are discharged from underneath the box or hopper *U*, said drops being directly over the discharge-opening at the bottom of the box or hopper. The drops may be either of wood or metal, and loaded at their outer ends, if necessary.

Y Y represent two ways or guides, which are placed transversely on the framing *A* above the ways *r r*. On these ways or guides *Y Y* a reciprocating planer, *Z*, is placed, the same consisting of a bar, *w*, with end pieces attached, between which two rectangular bars, *a' a'*, are secured by pivots, one at each side of bar *w*, and both parallel with it. To the lower outer sides of the bars *a' a'* there are secured metal plates *b'*, one to each, and the two bars *a'* are connected at one end by rods *c'*, which cross each other at their upper ends and are secured together by a pin, *d'*, said pin passing through any of a series of holes in said bars. By adjusting the pin *d'* in different holes the bars *a'* and their plates *b'* may have a more or less inclined position given them, as may be desired.

A'' represents two metal plates or cleaners, the ends of which are secured to oblique standards *e''* at the ends of bars *B' B'*, which are secured at their centers to the framing *A* by pivots *f'*. The bars *B'* are of such a length that there will be a cleaner, *A''*, at each side of the planer *Z*. The bars *B'* are allowed a slight rocking play or movement under the action of the planer, which has a reciprocating movement given it by a pitman, *g'*, attached to a crank, *h'*, on a shaft, *C'*, which is driven

by a belt, *i'*, from a shaft, *D'*, rotated by a bevel-pinion, *j'*, from the wheel *m* of shaft *N*.

E is a water tank or reservoir provided with a cock, *F'*, to which an elastic tube, *G'*, is attached, leading into a trough, *H'*, on the top of the planer *Z*, and *k'* represents pipes which extend from said trough down at each side of the planer to the plates *b'*, as shown in Figs. 1 and 2.

The operation of the machine is as follows: The molds *C* are sanded by placing them in the box *B* and turning it half a revolution, as previously described. As a sanded mold is removed from the box *B* it is placed on the bed or platform *F* in front of the bar *G*, the latter being drawn back by its weight *M*, and when the mold is perfectly adjusted in front of *G* the operator, by actuating the lever *L*, throws the pinion *H* of shaft *I* in gear with the rack *i* of bar *G*, and the mold is thereby shoved along underneath the box or hopper *U* and upon the rollers *s*. As soon as the mold *C* reaches its proper position underneath the box or hopper *U*, a pin, *a''*, which projects from the bar *G*, strikes the toggle *K* and throws the pinion *H* out of gear with the rack *i* of bar *G*, and the weight *M* then draws bar *G* back to its original position. The mold *C*, underneath the box or hopper *U*, has the clay pressed into it by the rotation of the wheels *V V*, the spiral arms or flanges *m* of the latter forcing the clay downward and compacting it well into the molds. The blades or arms *X* temper and cut or grind the moistened clay in *U*, reducing it to a proper state for the molds. The wheels *V* can only exert a certain pressure on the clay, owing to the spaces *o* through which the clay is fed down to the molds. The stationary cross-bars *p* serve to prevent the clay being rotated in the box or hopper *U* under the action of the wheels *V*. When the mold underneath *U* is filled, the operator puts another empty mold in front of bar *G* and actuates lever *L*, so as to throw the pinion *H* in gear with the rack of bar *G*, and the latter again moves forward, and in shoving an empty mold underneath *U* shoves out the filled mold, which passes underneath the drops *v*, the latter smoothing the upper surface of the same, and using one or any number of them to admit of the passage of any stones or projecting foreign substances, if the mold should happen to contain such. By this means the molds are prevented from being broken or injured—a contingency which would occur if the molds were forced out under an unyielding plate. The filled mold is then shoved by a succeeding mold passing under *U* under the planer *Z*, the plates *b' b'* of the bars *a'* of which scrape off the surface of the mold both ways from the center outward, thereby performing smooth work—a result which cannot be attained by scraping in one way only entirely across the mold, as the scraper will in that case drag the clay away from the edges of the mold. As the planer vibrates it has a slight rocking motion, which is given to it by the pitman *g'*, the latter

being permanently attached to the former, and this motion causes the water to flow from the trough H' down through the pipes K' to the mold, the clay therein being moistened, so that the scraping operation may be performed smoothly. The cleaners A'' keep the plates b' free from clay, the latter passing over the former at each vibration of the planer, the tilting or rocking motion of the bars B' , produced by the motion of the plates b' , causing cleaners A'' to be presented properly to said plates as the latter come in contact with the former, the action of one plate b' on its cleaner depressing it and elevating the other, so that it will be in readiness to clean its plate.

The rotation of the shaft T may be stopped at any time by shifting the clutch O^x , through the medium of a rod, b^x , and lever c .

We do not claim the blades or arms X on the rotating-shaft T , for they have been previously used, nor do we claim the rollers s underneath the box or hopper U ; but

What we do claim as new, and desire to secure by Letters Patent, is—

1. The feeding-bar G , provided with the rack

i , and having the weight M attached, in combination with the pinion H and toggle K , all arranged as and for the purpose specified.

2. The drops v , arranged as shown, to yield or give to obstructions in the molds, as the latter are forced out from underneath the box or hopper, as described.

3. The reciprocating-planer Z , provided with the adjustable plates or scrapers $b' b'$, to operate as set forth.

4. In combination with the plates $b' b'$, the cleaners $A'' A''$, arranged as shown, to operate as and for the purpose specified.

5. The water-tank E' and trough H' , the former being connected with the latter by an elastic tube, G' , and the trough H' provided with pipes k' , all arranged, as shown, to operate in connection with the reciprocating planer Z , for the purpose set forth.
